Application June 20, 1929, Serial No. 372,320

16 Claims. (Cl. 250—40)

This invention relates to the art of radio reception, and its object is to provide a device of novel construction and improved operation for remotely controlling a radio receiver.

5 One feature of my invention comprises time-controlled mechanism for automatically operating a radio receiver at predetermined intervals to tune in a series of selected stations in prearranged sequence. In this way a diversified radio 10 program lasting many hours is automatically brought in without personal attention.

My novel control device in its preferred form also makes it possible to tune in a desired station at any time by merely pressing a key or button. This automatic tuning operation is independent of the time-controlled feature and enhances the utility of the invention.

I may also provide a manual tuning key which causes operation of the radio shaft as long as the 20 key is held down, so that the entire dial is swept across the tuning point. When the operator gets the broadcast he wants, he simply releases the key and the station remains tuned in. The key-controlled operations mentioned can 25 not take place as long as the time-control is on, because during that period the keys are automatically locked.

The control mechanism of my invention is housed in a small portable cabinet conveniently 30 located at any distant point from the radio receiver. An electric cable containing all the necessary wiring connects the receiver with the control cabinet. A clock in the cabinet controls a series of switches, and these in turn control the 35 operation of an electric motor that drives the tuning shaft. This motor is also controlled by the automatic tuning keys and the manual tuning key carried by the cabinet to bring the radio shaft into the desired tuning position. The cabinet 40 not usually has an indicating dial, a volume control knob and a power switch, so that the radio receiver can be fully controlled from a distance in every respect.

The novel features and practical advantages 45 of my invention will be understood from a description of the accompanying drawings, in which—

Fig. 1 shows a front view of a control cabinet constructed in accordance with my invention;

50 Fig. 2 represents a vertical side section on line 2—2 of Fig. 3;

Fig. 3 is a plan view on the broken section line 3—3 of Fig. 2, the clock mechanism being omitted for clearness;

55 Fig. 4 is a fragmentary perspective view, partly

in section, showing one of the automatic tuning keys and associated mechanism;

Fig. 5 is a fragmentary perspective view of the manual tuning key and certain devices associated therewith;

Fig. 5A shows a fragmentary perspective of 5 one of the motor controlling switches associated with the tuning shaft of the radio receiver;

Fig. 6 represents an inner face view of the 10 switch mechanism associated with the clock in the control cabinet, this view being taken on section line 6—6 of Fig. 2;

Fig. 6A is an enlarged fragmentary view in 15 section to show certain switch connections controlled by the clock;

Figs. 7, 8 and 9 show structural details of the 20 plug and jack connections surrounding the clock in the cabinet;

Fig. 10 shows the driving and controlling 25 mechanism associated with the tuning shaft in the radio receiver, this view being taken on line 10—10 of Fig. 11;

Fig. 11 is a side view of the mechanism shown in Fig. 10, looking from right to left;

Fig. 12 shows an enlarged plan view of the 25 connections for operating the tuning shaft by hand, this view being partly a section on line 12—12 of Fig. 10;

Fig. 13 is a fragmentary detail view showing 30 one of the motor control switches in closing position, this switch device being the same as that shown in Fig. 5A;

Fig. 14 shows a face view of a magnetic clutch member for connecting the tuning shaft with the driving motor, this view being taken on line 35 14—14 of Fig. 10; and

Fig. 15 is a diagram of the electric circuit 40 connections that establish certain operative relations between the control cabinet and the tuning shaft of the radio receiver.

Before taking up a detailed description of the 45 various mechanisms contained in the control cabinet and the radio receiver, I think it will facilitate an understanding of my invention if I first describe in a general way the various operations or results obtainable from the control cabinet.

Referring to Fig. 1, there is a suitable cabinet C having a front panel 10 from which project various hand-operable members for performing 50 certain operations. A switch lever 12 turns the electric power on or off, this lever operating a main switch of any suitable construction. When this switch is open, all circuit connections for the control cabinet and the radio receiver are 55

cut off, so that no current is wasted. A knob 13 controls the volume of reproduction in any practical way. By depressing a key 14 the operator connects the tuning shaft with an electric motor 5 which drives the shaft as long as the key is held down. When the operator gets the desired station or broadcast reception, he releases the key and the station remains in tune. At the bottom of the cabinet are five tuning keys 15, which I 10 have differentiated by the suffixes *a*, *b*, *c*, *d* and *e* to indicate that they represent certain preselected stations that are automatically tuned in when a control key is actuated. In operating these 15 automatic tuning keys, it is not necessary to hold a key down to get the desired station. The connections are such that an actuated key is locked against return until the selected station is tuned in. Through windows 16 and 17 of the front panel are seen respectively a drum 18 which carries 20 wave length or frequency notations, and a drum 19 on which the stations are identified by their call letters. The drums 18 and 19 always rotate in unison and inform the operator which station is on the air and the assigned wave length or frequency of that station.

In the upper portion of cabinet C is a clock whose dial 20 is surrounded by jacks 21 arranged in concentric circles. Each circle of jacks represents a selected station, and in this case there 25 are five circles of jacks because five stations have been arbitrarily chosen by way of illustration. It has been my experience that almost any locality can get all the desired broadcast programs through a few stations. The jacks 21 are 30 also arranged in radial lines representing hours and half-hours on the clock. Most stations come in on the hour and some on the half-hour. A closer arrangement of jacks to represent quarter-hour intervals is hardly necessary. Contact plugs 35 22 are adapted to be inserted in jacks 21 to tune in a number of selected stations at certain hours in predetermined sequence. For distinction I have marked the different plugs 22 by the suffix 40 letters *a* to *e*. Fig. 1 shows five plugs inserted 45 in the different circles of jacks 21 to bring in five successive stations from seven o'clock to eleven o'clock. As the hands of the clock move around, the selected stations are automatically 50 tuned in in the order selected, so that a whole evening's, or even a whole day's, radio program may be brought in without attention by anybody. The plugs 22 are independently movable and may 55 be inserted in the jacks 21 to bring in any station at any time during the broadcasting period. This automatic time-control of the tuning shaft 60 can be cut out by a switch member 23 when it is desired to use the automatic tuning keys 15, which operate independently of the time control. As long as the time-control switch member 23 is 65 on, the manual tuning key 14 and the automatic tuning keys 15 are locked against operation. This makes the control cabinet fool-proof and prevents the possibility of disorganizing any part of the interior mechanism.

I shall now describe in detail the mechanism 70 inside the control cabinet C. For this purpose I shall refer mainly to sheets 2, 3 and 4 of the drawings. A bracket 24 is rigidly secured to the back wall 25 of cabinet C by bolts or other fastening members 26 which pass through lateral flanges 27 of the bracket. This supporting bracket, which is preferably an aluminum casting, is provided with three hubs or bearings 28, 29 and 30. The bearing 28 supports a rotary 75 shaft 31, which carries a worm or spiral gear 32

arranged in mesh with a worm 33 on the driving shaft 34 of a suitable electric motor 35. The latter is rigidly mounted on the bottom plate 36 of cabinet C, as by screws 37 or otherwise. The bearing or hub 29 supports a shaft 38 which 5 carries a gear sector 39. A link 40 connects the worm gear 32 with gear sector 39, so that continuous rotation of the worm gear produces oscillating movements of the gear sector. The ends of link 40 are mounted on pins 41 and 42 carried 10 by the gear members 32 and 39 respectively. The gear sector 39 is in mesh with a gear wheel 43 fixed on a rotary shaft 44 which passes through the bearing 30 of bracket 24. The ends of shaft 44 are journalled in suitable bearings 45 secured 15 to the sides 46 of the cabinet. The shaft 44 also carries the indicator drums 18 and 19 previously referred to. The driving connections between the motor shaft 34 and indicator shaft 44 are such that continuous rotation of the motor shaft 20 produces rotation of the indicator shaft for a half-revolution in alternately opposite directions. The speed of the indicator shaft is preferably 25 about the same as when a radio shaft is tuned by hand. In my own experience, I have found that, 25 in ordinary hand tuning to get a station by ear, it takes about thirty seconds to turn the dial through its full range of movement. The speed of the indicator shaft 44 may vary to suit specific requirements in different designs of control 30 cabinets. In a simpler form of my invention, the indicator drums 18 and 19 may be omitted, together with the electric motor 35 and the associated driving connections. While it is convenient, and perhaps even desirable, to have a 35 station indicator in cabinet C, that is not absolutely essential, because the stations automatically brought in are identified by the circles of jacks 21 and by the tuning keys 15.

The manual tuning key 14 comprises a shank 40 47 pivoted on a pin 48, which is supported in a sleeve or hollow post 48' projecting from the adjacent side 46 of the cabinet, as best shown in Figs. 2 and 5. A contracting coil spring 49 normally holds the key shank 47 in uppermost position against a suitable stop, which in the present instance is the upper end 50 of the slot 51 through which the key projects out of the cabinet. The upper end of coil spring 49 is connected to a screw-eye 52 secured to the front panel 10 of the cabinet. The key shank 47 has a rear extension 53 and a depending extension 54. The parts 47, 58 and 54 may conveniently be formed as a single member stamped from sheet metal, preferably aluminum, which is light and strong. The extension 53 is adapted to be engaged by a catch 55 pivoted on a pin 56, which is supported in a sleeve or bushing 57 projecting from the adjacent side 46 of the cabinet, as clearly shown in Fig. 5. A contracting coil spring 58 normally holds the 60 catch 55 against a fixed stop 59 out of the path of extension 53. One end of spring 58 is secured to catch 55, and the other end is connected to a pin or lug 60 projecting from the side wall of the cabinet. The lower end of the pivoted catch 65 55 is connected to the magnetic core or plunger 61 of a solenoid coil 62. A convenient way of connecting the members 55 and 61 is to bifurcate the latter, as indicated at 63 in Fig. 5, to receive the lower end of member 55. A pin 64 pivotally 70 connects the lower end of catch 55 with the solenoid core 61. The coil 62 is rigidly supported on a suitable block or bracket 65 by means of a strap 66 or otherwise. The block 65 may conveniently be attached to the bottom or side of the cabinet. 75

It is clear from Figs. 2 and 5 that, when the solenoid 62 is energized, the upper end of catch 55 is rocked over the extension 53, so that the key 14 is positively locked against operation.

Referring to Fig. 5, an insulating block or bracket 67 extending from the cabinet wall 46 carries a pair of switch arms 68 and 69, which may conveniently be secured in slots 70 of block 67 by a screw or bolt 71. At least one of the switch arms 68 and 69 is of spring metal, which is so positioned that the switch is normally open. When the key 14 is pushed down, the extension 54 rocks rearward and forces the spring arm 68 against the arm 69 to close the switch, which remains closed as long as the key is held down. The function of this switch is to control the electric motor that drives the tuning shaft, as will be explained in due course.

I shall now describe the construction and operation of the automatic tuning keys 15. Since these keys are alike, a detailed description of one is sufficient for all, and for this purpose I shall refer mainly to Figs. 2, 3 and 4, particularly the latter. Each key 15 comprises a shank 72 formed with a rear extension 73, an upper extension 74 and a lateral projection 75. All these parts may consist of a single member stamped from sheet metal. The key shanks 72 are pivotally mounted on a common shaft or rod 76, which is supported at its ends in suitable brackets 77 secured to the side walls of the cabinet. Each key shank 72 has a bushing 78 arranged between a pair of fixed collars 79 on shaft 76, whereby the keys are held against lateral movement while being freely pivoted on the shaft for independent operation. Each key 15 is held in normal uppermost position by a contracting coil spring 80, which is connected at one end to the shank 72 and at the other end to a screw-eye 81 secured to the front panel of the cabinet. As in the case of the manual key 14, the keys 15 may be normally held by the coil springs 80 against the upper edges of the slots 82 through which the keys 15 project at the front of the cabinet.

Across the width of cabinet C extend three flat insulating bars 83 and 84, supported at their ends by a pair of slotted blocks or brackets 85. The central bar 83 acts as a spacing strip for the two side bars 84, and these three bars are suitably connected to form a rigid insulating support for a set of switches controlled by the keys 15. Each of these switches consists of a pair of contact arms 86 and 87, which are normally separated to hold the switch open. A convenient way to mount the switch arms in the insulating support 83-84 is to provide each arm with an opening 88 adapted to receive a lateral lug or projection 89 on the adjacent side bar 84, as clearly shown in the perspective view of Fig. 4. In this way, the mere connection of the bars 83-84 automatically clamps the spring arms 86 and 87 rigidly to the support without additional fastening means. Of course, there are other ways of mounting the pairs of switch arms 86-87 and my invention is not limited to any detail in this respect. The upper extension 74 of each key 15 is bent forward at 74' to engage the switch arm 86 and move it into contact with the arm 87 when the key is pushed down. This will be clear from Figs. 2 and 4.

A base plate 90 secured to the bottom of the cabinet carries an insulating bar or block 91 below the transverse shaft 76. The block 91 is a common support for a series of solenoid coils 92, one for each key 15. As shown in Fig. 4, the coils 92

are set in recesses in block 91 and held in place by straps 93. Each coil 92 has a magnetic core or plunger 94, which is pivotally connected by a pin 95 to a locking pawl or dog 96. A suitable bracket 97 on base plate 90 carries a pin 98 on which the dog 96 is pivoted. A spring 99 normally holds the locking dog 96 in a forward position out of the path of movement of the transverse lug 75 on key 15, so that the latter is free to be actuated. When the solenoid 92 is energized, the core 94 is pulled in until the upper end of dog 96 strikes the transverse lug 75. As long as the coil remains energized, the associated key 15 can not be pushed down. The rear extension 73 of key 15 carries a cross-pin or lateral lug 100 arranged to be engaged by a locking dog 101 pivoted on a pin 102 which is supported in a suitable bracket 103 fixed on the base plate 90. Each dog 101 has a locking shoulder 104 adapted to snap into locking engagement with the cross-pin 100 of the associated key when the latter is pushed down. A contracting coil spring 105 is connected at one end to each locking dog 101, and the other ends of these springs are connected to the fixed insulating support 91, as indicated at 106 in Fig. 4. The springs 105 normally hold the pivoted dogs 101 against the cross-pins 100. When a key 15 is pushed down, the rear pin or lug 103 moves up until it enters the locking recess or shoulder 104 of the associated dog 101, which is held forward in locking position by the connected spring 105. This will be clear from Figs. 2 and 4. It should be noted that the locking dogs 101 are independently operable, so that the actuation of any key 15 moves only the associated dog into locking position. The purpose of holding an actuated key down is to keep the switch 86-87 closed until the electric motor which operates the tuning shaft has performed its intended function. This will be better understood when I describe the various circuit connections later on. At this point I merely wish to make it plain that when a person operates one of the automatic tuning keys 15, he can remove his finger as soon as the key is down and the associated locking dog 101 holds the key in depressed position until the selected station is tuned in.

The individual locking dogs 101 are restored to normal position by a common rod 107 arranged transversely in front of the dogs and supported at its ends in a pair of bellcranks 108 which are pivoted on a cross-bar 109. The ends of bar 109 are held in suitable brackets 110 on the sides of the cabinet. Instead of a single supporting bar 109, I may use two separate pins 112 for pivoting the bellcranks 108. One or two springs 112 connected to the bellcranks 108 hold the latter in a forward position against suitable stops 113, so that the rod 107 permits forward movement of the locking dogs 101. The rear arm 114 of each bellcrank 108 is pivotally connected to a magnetic core or plunger 115 arranged to reciprocate in a solenoid coil 116, which is rigidly supported in any practical way. When the coils 116 are energized, the bellcranks 108 are rocked rearward (clockwise as viewed in Fig. 4), so that the transverse rod 107 strikes any dog 101 that happens to be in locking position and moves it back to release the depressed key 15, which is instantly raised to normal position by the connected spring 80. Only one coil 116 is necessary, especially if it be arranged centrally of the restoring rod 107, and I have shown two restoring coils merely to provide an actuating force at each end of the rod.

A bracket 117 secured to the top of cabinet C supports a suitable clock K. The dial 20 of this clock is here set into, or made part of, an insulating disk 118 which fits into an opening 119 in front panel 10 of the cabinet. Screws 120, or other fastening means, hold the disk 118 rigidly in place. The disk 118, which is preferably molded of suitable insulating material, such as Bakelite, carries the jacks 21 previously referred to in connection with Fig. 1. The construction of these jacks is best shown in the enlarged views of Figs. 7, 8 and 9. Since the jacks 21 are alike, it is only necessary to describe one of them. Each jack comprises a sheet metal sleeve or thimble 121 set firmly in an opening 122 of disk 118. The sleeves 121 of each circle of jacks are firmly connected to a sheet metal ring 123, which is provided with properly spaced openings 124 surrounded each by a short cylindrical flange or bushing 125. When the sleeves 121 are inserted into the openings 124 of ring 123, the flanges 125 grip the sleeves in a tight fit, and not only hold them firmly in place but also connect them in good electrical contact with the ring. The sleeves 121 and ring 123 should be made of good conducting metal, like brass. The plugs 22 comprise a cylindrical metal shank 126 adapted to fit snugly in the sleeves or thimbles 121, which may be provided with a spring tongue 127 arranged to snap into a circular groove 128 in shank 126, whereby the plug is held in fully inserted position and remains in good electrical contact with sleeve 121. The latter may be inserted into the holes 122 of disk 118 after the same has been molded, or the sleeves may be mounted on the concentric rings 123 before the composition material is poured into the mold. There are doubtless other ways of mounting and connecting the jacks 21, and the particular construction just described is to be considered merely by way of example.

The insulating disk 118 carries on its inner face a series of spring contact strips 129 arranged over the rear openings 130 in disk 118. In other words, the radial spring strips or fingers 129 are in line with the radial rows of jacks 21 appearing on the front panel 10 of the cabinet. The contact fingers 129 are secured to disk 118 in any practical way, as by screws 131. When a plug 22 is fully inserted in a jack, the projecting end 132 (see Fig. 8) pushes the adjacent spring finger 129 slightly to the rear, so that a firm pressure contact is established between those two parts. The contact fingers 129 are engaged by a conducting arm 133 fixed on the hollow shaft 134 that carries the hour hand 135, as best shown in Fig. 6A. The rotary arm 133 is always in electrical contact with a fixed plate 136 carried by the insulating disk 118. If desired, a small spring blade 137 may be attached to the arm 133 to maintain good electrical contact with plate 136. A rod or stiff wire 138 is connected at one end to plate 136 and at the other end to a circuit lead 139. The conductor 138 may be placed in a radial groove in disk 118, so as to be out of the way of arm 133, if that should be found necessary.

It will be clear from the preceding paragraph that the contact arm 133 is in effect a rotary terminal of the circuit lead 139, so that the radial fingers 129 are successively connected to conductor 139 as the hour hand of the clock moves around. The contact arm 133 and hour hand 135 are always in radial alignment and move 75 as a unit. The number of minutes during which

the arm 133 remains in contact with a jack strip 129 depends upon the width of the contact area and that can be regulated as required. The contact between members 129 and 133 need only be long enough to allow the electric motor to rotate the radio shaft into tuning position, and that takes only a fraction of a minute. The disk 118 is formed with a recess 140 in which the dial 20 is located and which allows space for the hands of the clock. The recess 140 is closed by a sheet 10 metal cover 141, which fits into the recess and is removable or swings open to permit access to the hands and for winding the clock. It is evident that the minute hand of the clock may be used in conjunction with the hour hand to close the circuit through an inserted plug on the exact minute. This will be understood without additional illustration. In the broad aspect of my invention, any other practical time-controlled switch connections may be employed. 20

Referring to Figs. 2 and 3, the bracket or casting 24 carries a pin 142 on which an insulating arm 143 is pivoted. This arm is provided with a pair of metal plates or extensions 144 and 145, which may conveniently be attached by screws 146. An insulating bracket 147 secured to casting 24 carries a contact button 148 arranged to be normally out of engagement with plate 144. Another insulating bracket 149 on casting 24 carries a contact button 150, which is normally engaged by the plate or metal extension 145 of the pivoted arm 143. A coil spring 151 connected to arm 143 normally holds the plate 145 in firm pressure contact with button 150, while the switch members 144 and 148 are kept apart. The pivoted arm 143 carries an armature 152 in operative relation to an electromagnet or solenoid 153, which is supported on a suitable bracket 154 on the casting 24. When the electromagnet 153 is energized, the armature 152 is attracted and the switch arm 143 is rocked clockwise (as viewed in Fig. 2) to close the switch contacts 144—148 and at the same time open the contacts 145—150. The circuit connections of these switches will be subsequently explained in detail, but I may say here that the closing of switch contacts 144—148 closes the circuit of solenoids 116 to operate the key-restoring bar 107, while the opening of switch 45 145—150 breaks the motor circuit and stops the tuning shaft. 50

Referring again to Fig. 3, the finger pieces 12 and 23, which are shown as toggle levers, are parts of suitable switch devices indicated diagrammatically by the rectangular outlines 155 and 156, which may be considered as representing the casings in which the switch parts are housed. It will not be necessary to show the structural details of switch 155, because any kind of on-and-off switch will do. As for the switch operated by finger piece 23, I shall explain that in connection with Fig. 15. The rotary knob 13 is supposed to operate any suitable device 157 for controlling the volume of reproduction. The structural details and electrical connections of a volume controlling device need not be shown or described, because they form no part of this invention, and are readily understood by those skilled in the art. There are various ways of controlling the volume of a radio loudspeaker, and it is sufficient to say that the device 157, which is controlled by knob 70 13, is operatively connected with the radio receiver to regulate the volume of reproduction. 65

I now come to the mechanism mounted in the radio receiver cabinet for operating the tuning shaft. This mechanism is illustrated on sheets 75

5 and 6 of the drawings, and certain details are also shown in the perspective view of Fig. 5A. The cabinet containing the radio receiver and associated mechanism is conventionally shown as a rectangular box R of suitable dimensions and design. Of the apparatus necessary for radio reception, no illustration or description is necessary, because we are here concerned only with the operation of the rotary shaft 158 on which 5 the tuning condensers 159 are mounted. These condensers may be of any suitable construction to permit the regulation of capacity by rotation of shaft 158 in either direction. The back wall 160 of cabinet R carries a casting 161 secured by bolts 162 or otherwise. Referring to Fig. 10, it is seen that the casting 161 has a right-angled arm 163 which terminates in a bearing 164 for one end of the condenser shaft 158. The other end of this shaft is supported in a suitable bearing 165. 10 The supporting frame or casting 161 is provided with three bushings 166, 167 and 168. A worm or spiral gear 169 is rotatably supported in bushing 166 and is permanently in mesh with a worm 170 on the drive shaft 171 of an electric motor 172, which is suitably mounted on the bottom plate 173 of the radio cabinet. The hub or bushing 167 of frame 161 supports a rotary gear sector 174, which is operatively connected to the worm gear 169 by a link 175. The ends of this 15 link are pivotally connected to pins 176 and 177 carried by the gear members 169 and 174 respectively. The gear sector 174 is in mesh with a gear wheel 178 fixed on a shaft 179, which is journalled in the upper hub 168 of the supporting frame 161. By comparing Figs. 2 and 11, it will be observed that the driving connections between the electric motor 35 and the dial shaft 44 in Fig. 2 are the same as the driving connections between the electric motor 172 and shaft 179 in Fig. 11. Therefore, when the two electric motors are energized, the shafts 44 and 179 are rotated in unison at the same speed. It is assumed that either the loads on the two motors are substantially the same, or that the motor having the 20 lighter load receives correspondingly less current, as regulated by an ordinary rheostat. For example, the indicator shaft 44 in the remote control box may carry a brake or other artificial load to equal the load on the tuning motor 172 in the radio cabinet. As every electrical engineer knows, synchronizing devices for electric motors are old and well understood, so I need only repeat that any suitable means may be employed to produce synchronous movement of the motor-driven shafts 44 and 179. In this instance it has 25 been assumed that the tuning shaft 158 of the radio receiver encompasses the entire broadcasting field by rotation of half a revolution. For this reason the shafts 44 and 179 oscillate back and forth through a radius of 180 degrees, while the gear wheels 32 and 169 are driven continuously in the same direction at properly reduced speed. This automatic reversal of operation of shafts 44 and 179 is accomplished by means of the connecting links 40 and 175 and their respective gear sectors 39 and 174.

70 Referring to Fig. 10, the inner end of shaft 179 carries a magnetic clutch disk 180 of suitable construction. In this case the disk 180 has pole pieces 181 which carry magnetizing coils 182, as best shown in Fig. 14. The electric current is led through these coils by means of a pair of insulated contact rings 183, which are constantly engaged by a pair of brushes or other contact members 184. These brushes may conveniently

be mounted on an insulating block or extension 185 secured to the main frame 161. The right end of condenser shaft 158 carries a magnetic armature disk 186, which is slidably mounted on the shaft by means of a key 187. It is seen in Fig. 10 that the shafts 158 and 179 are substantially in axial alignment and are normally disconnected. This permits the tuning shaft 158 to be operated by hand in the usual way. When the clutch coils 182 are energized, the slidable armature disk 186 is instantly attracted to the pole pieces 181 and held with such force to the polar faces that the shafts 158 and 179 become coupled to operate as a single member. When the circuit of the clutch coils 182 is interrupted, the armature disk 186 is immediately released and the tuning shaft 158 becomes disconnected from the clutch shaft 179. If desired, a retracting spring may be inserted for the armature disk 186, but as a rule that is not necessary, because the armature moves away sufficiently from the demagnetized pole pieces 181 to cause uncoupling of shaft 158 from shaft 179. 10

20 Referring to Figs. 11 and 12, the front panel 188 of radio cabinet R carries a hand knob 189 for operating a shaft 190, which is provided at its inner end with a bevel pinion 191 arranged in mesh with a second bevel pinion 192 fixed on a shaft 193. A bracket 194 is provided with a bearing 195 for shaft 190 and with a bearing 196 for shaft 193. The tuning shaft 158 carries an indicator drum 197, which is supposed to be a duplicate of the indicator drums 18 and 19 in control cabinet C. All these drums may conveniently be cast of aluminum on account of 25 its lightness, or they may be shaped from sheet metal, like brass, and marked on the periphery with appropriate notations. The indicator drum 197 carries an internal gear 198, which meshes with a pinion 199 on shaft 193. By means of the 30 connections above described, the tuning shaft 158 and drum 197 can be operated manually at reduced speed by turning the knob 189 in one direction or the other. The markings on drum 197 are visible through a sight opening 200 in the 35 front panel 188 of the radio cabinet. It should be noted that the manual driving connections do not interfere with the operation of the tuning shaft by the electric motor 172. The manual operation of tuning shaft 158 is not absolutely 40 necessary, because the electric motor 172 can always be used. In that case it is only necessary to provide the radio cabinet with a manual tuning key, like the key 14 on the remote control cabinet C, to control the circuit of the driving motor. When the hand operation of the radio shaft is dispensed with, the magnetic clutch 180-186 is not necessary, because in that case the tuning shaft can be permanently coupled to the motor. If the tuning knob 189 is used 45 for turning the condenser shaft 158 by hand, independently of motor 172, the clutch 180 is preferably inserted between the gear 169, and the motor shaft, so that the relation of the tuning shaft and the automatic reversing mechanism 50 remains fixed. This will be clear to any mechanician. 55

60 Referring to Figs. 10 and 13, the tuning shaft 158 carries a series of disks 201, which are alike in structure and which I have differentiated by 65 the suffix letters a to e, respectively, to indicate that each disk represents a certain selected station. These disks are preferably cast or molded of insulating material, such as Bakelite, and they are held in spaced relation on shaft 158 by 70 75

integral hubs 202, which are secured to the shaft by pins 203 or otherwise. Each disk 201 is provided with a contact piece 204 extending axially across the periphery of the disk and arranged in 5 predetermined radial position, in accordance with the station represented by the disk. The contact pieces 204 may be rigidly fixed to the disks 201, as by being molded in place, but I prefer to mount them in such a way that their radial position can be adjusted for any station on the dial. As best shown in Fig. 13, the peripheral contact 204 is an integral lateral extension of a 10 spring arm 205 which has an annular washer-like enlargement 206 fitting over the hub 202 of the disk and held in place by the pin 203. The adjacent face of disk 201 is formed with radial grooves or corrugations 207 adapted to receive a radial rib 208 on the spring arm 205. The 15 normal tension of arm 205 holds the rib 208 in firm frictional locking contact with the grooved face 207 of disk 201 in any position to which the arm 205 may be adjusted. This frictional locking contact, however, is sufficiently yieldable to permit radial adjustment of the contact arm 205 20 relative to the disk. For this purpose the arm 205 has a lateral lug 209 which may be struck up as an integral extension of the arm. By inserting a suitable instrument into the cabinet to engage the lug 209, the tuning shaft may be 25 turned by hand to move the disk 201 while the contact arm 205 is held stationary. In this way it is a simple matter to adjust the radial position of any contact 204 on its supporting disk 201.

30 Each disk has associated with it a pair of insulated switch arms 210 mounted on a block 211, which may be molded of insulating material. The supporting blocks 211 are pivoted individually on a common shaft 212 and held spaced by 35 bushings 213. The ends of shaft 212 are supported in side brackets 214, which are rigidly connected at the top and bottom by cross pieces 215 and 216 to form a unitary supporting frame for the series of switches 210 and the associated actuating mechanism. The bracket 194, which supports the shafts 190 and 193, as I have previously mentioned, may conveniently be attached to the bottom plate 216. A convenient way of securing the framework 214-216 in the cabinet is 40 to provide the base plate 216 with a flange 217 adapted to receive suitable fastening members 218 for attaching the frame to the inner wall of the front panel 188. This is clear from Figs. 5A and 11. The unitary mounting of all the switches 45 210 and their associated actuating mechanism makes it possible to assemble the parts completely before inserting the frame 214-216 into the radio cabinet.

50 The base plate 216 supports a series of electromagnets or solenoids 218, which I have differentiated in Figs. 10 and 15 by the suffix letters *a*-*e* as a convenient way to indicate that they are associated, respectively, with the tuning disks 201*a*-201*e*. Each block 211 carries an armature 219 adapted to be attracted by the electromagnet 218 when the same is energized. A coil spring 220 normally holds each pivoted block 211 in the position shown in Fig. 11—that is, with the rear portion of the block raised so that 55 the switch arms 210 are out of contact with the associated disk 201. A fixed rod 221 supported between the side brackets 214 acts as a common stop for the pivoted blocks 211 under the action of springs 220. When an electromagnet 218 is 60 70 75 energized, the associated block 211 is rocked into

the position shown in Fig. 13 to hold the switch arms 210 in pressure contact with disk 201. As soon as the electromagnet is de-energized, the spring 220 quickly moves the block 211 into the position shown in Fig. 11.

5 Referring to Figs. 5A, 11 and 13, each pivoted block 211 also carries a switch arm 222, which may simply be a strip of spring brass inserted at one end in a slot in the block, as best shown in Fig. 13. The cross-bar 215 carries a series of 10 insulated contact buttons 223 arranged to be engaged by the switch arms 222 when the blocks 211 are actuated into circuit-closing position, as shown in Fig. 13. When the blocks 211 are in normal position, as illustrated in Fig. 11, the 15 movable switch arms 222 are separated from the fixed contacts 223. Since each switch arm 222 and its associated contact 223 constitute a switch, I have indicated this series of switches in the 20 circuit diagram of Fig. 15 by the reference numeral 223 with the suffixes *a*-*e* for distinction. That makes it easier to trace the circuits.

In the first part of this specification, I have 25 stated that the finger piece 23 on the front panel 10 of the remote control cabinet C operates a switch device to throw the time mechanism into and out of operation. A simple form of switch controlled by the finger piece 23 is shown 30 diagrammatically in Fig. 15. The hand member 23 is connected to a cylinder or drum 224, which 35 is pivoted on a shaft indicated by the dotted line 225. The drum 224 has a lug or extension 226 arranged between a pair of fixed stops 227 and 228. A contracting coil spring 229 connected to the drum above its pivot is so arranged 40 as to hold the lug 226 against the "off" stop 227 or the "on" stop 228. The switch drum 224 controls two switches indicated diagrammatically by two pairs of contact arms 230 and 231. In the 45 actual device, these switch arms would be arranged side-by-side, but in the diagrammatic drawing of Fig. 15 I have displaced them laterally. For this reason it was necessary to represent the drum 224 in two sections connected by the dotted axial line 225. The toggle drum 224 is provided with a projection 232. When the 50 toggle lever 23 is in "off" position, as shown in Fig. 15, the switches 230 and 231 are open, it being assumed that the switch arms are normally held open by inherent tension. When the finger piece 23 is thrown to the right (as viewed in Fig. 55 15), the projection 232 moves the lower switch arms 230 and 231 into contact with the upper arms and thereby closes both switches.

I shall now describe the circuit connections in 55 Fig. 15. A switch plug 233 adapted to be inserted in an ordinary house-lighting socket is connected to a pair of mains 234 and 235. The switch operated by the toggle lever 12 is inserted in conductor 235, although it may obviously be placed 60 at any other point for opening and closing all circuits. The electric motors 35 and 172 are connected at one side to the circuit lead 235 by wires 236 and 231. The other side of each motor is connected to a wire 238 which leads to the 65 switch arm 68. I might explain here that I use the word "wire" in this description as a convenient term to include any kind of electrical conductor, without regard to form, shape, or material, provided only it is practical to use. A 70 wire 239 connects the switch arm 69 to the main conductor 234. It is clear from this that the motors 35 and 172 are connected to the power circuit in parallel through switch 68-69. When 75 this switch is closed by the manual tuning key 14, 75

the two motors are driven synchronously to operate the indicator shaft 44 in the control cabinet C and the tuning shaft 158 in the radio receiver. The circuit of clutch 180 is closed through wires 5 240 and 241, which are connected to the switch arms 184. The clutch circuit, like the motor circuits, is closed through the key-operated switch 68-69.

The switch contacts 210a-210e are connected 10 in parallel to a pair of conductors 242 and 243. Conductor 242 is connected at 244 to the main lead 235, while conductor 243 is connected to a wire 245 which leads to one side of the solenoid 153. The other side of this solenoid is connected 15 by a wire 246 to the circuit main 234 at point 247. The switch contacts 148 and 150 associated with solenoid 153 are connected to conductor 234 by wires 248 and 249. The contact plate 144 is connected by wire 250 to a conductor 251 which 20 leads to one side of the two solenoids 116. The other side of each solenoid is connected to a conductor 252, which in turn is connected at 253 to a wire 254 leading from the circuit main 235. The solenoids 116 are therefore connected in 25 parallel to the power circuit through switch 144-148.

The switch plate 145 carried by the pivoted arm 143 of solenoid 153 is connected to a conductor 255 from which parallel branch lines numbered 30 consecutively 256 to 269 lead respectively to the movable or lower contact arms of the five switches 223a-223e. The upper or stationary contacts of these five switches are connected by parallel branches marked consecutively 261 to 35 265 to a common conductor 266, which is connected at 267 to conductor 238. This means that the switches 223a-223e are connected to the power circuit in parallel through switch contacts 145-153, which is under the control of solenoid 40 153. The solenoids 218a-218e, which control the associated switches 210a-210e, are connected at one side in parallel to a conductor 268, which is connected at 269 to the circuit lead 234. The other sides of the solenoids 218a-218e are connected 45 by separate wires marked 270-274 to five conductors marked 275-279. One contact arm of each of the switches 86a-86e is connected to the common conductor 254, while the other contact arms of these switches are connected respectively to conductors 270-275, 271-276, 272-277, 50 273-278 and 274-279. The "dash" mark in the last sentence signifies that each pair of conductors is electrically connected to form in effect a single conductor.

55 In Fig. 15 I have distinguished the five circles of jacks 21 by the suffix letters a-e, so that the outer circle of jacks shall be called 21a, the next circle 21b, and so on. The connecting rings 123 have also been distinguished by suffix letters 60 a-e, and these circles have been shown in the form of lines to represent diagrammatically wire connections. It will thus be clear that the jacks 21a of the outer circle are electrically connected by a wire 123a, the jacks 21b of the next circle 65 are connected by a wire 123b, and so on for the other circles of jacks. The five connecting wires 123a-123e are connected respectively to conductors 275, 276, 277, 278 and 279. The conductor 139, which is connected to the rotary switch 70 arm 133 of the clock, leads to one of the switch contacts 231. The other contact of this switch is connected by a wire 280 to the circuit main 235. The lower contact arm of switch 230 is connected by wire 281 to one side of the solenoid 62, the other side of which is connected by wire 282 to

the circuit lead 235. The upper contact arm of switch 230 is connected by wire 283 to a conductor 284, which serves as a common connection for one side of the solenoids 92a-92e. The other side of these solenoids is connected to a conductor 285 which leads to the circuit main 234. In other words, the solenoids 92a-92e are connected in parallel to conductors 284 and 285, and the circuit of these solenoids can be closed only through switch 230 and solenoid 62. 10

Let us now assume that the time switch 224 is closed and that five plugs 22 are inserted in the positions marked 22a-22e in Fig. 15. We shall further suppose that the hands of the clock indicate the hour of seven, which means that 15 the rotary switch arm 133 is in contact with the radial strip 129 which is in line with the hour hand at this time. The plug 22e closes the circuit of solenoid 218e through the following connections: Circuit main 234 to point 269, wire 268, 20 coil of solenoid 218e, wires 274 and 279, contact ring 123e, through inserted plug 22e to radial strip 129, switch arm 133, wire 139, closed switch 231, wire 280, and return lead 235. When the solenoid 218e is energized, it rocks the associated 25 block 211 (see Fig. 13) and throws the switch arms 210e into contact with tuning disk 201e. This movement of block 211 closes switch 223e, whereby the motor circuits are closed through the following connections: Circuit lead 234, wire 30 249, through closed switch contacts 150-145, conductors 255 and 260, across the closed switch contacts 223e, wires 265 and 266 to point 267 of conductor 238. From there the circuit divides in parallel, one branch going through motor 35 35 and wire 236 to the return main 235, and the other branch going through motor 172 and wire 237 to the return main. At the same time, the circuit is closed through the coils of clutch 180 through wire 241, contact brushes 184, and wire 40 260. Consequently, the two electric motors operate simultaneously at the same speed and the clutch disk 186 is in coupling position, so that the tuning shaft 158 is operated by motor 172. At the same time, the motor 35 in the control 45 cabinet C operates the indicator drums 18 and 19 in synchronism with the indicator drum 197 of the radio receiver.

In addition to the closing of the various circuits above described, the solenoid 62 and the 50 five solenoids 92a-92e are energized to lock the manual tuning key 14 and the automatic tuning keys 15 against operation. These six solenoids are energized through circuit lead 234, conductor 235, solenoids 92a-92e in parallel, 55 conductors 284 and 283, through the closed switch 230, conductor 281, through solenoid 62, and by wire 282 to the return lead 235. The energized solenoid 62 rocks the dog or latch 55 into locking position against the rear end of key 14, and the 60 energized solenoids 92a-92e move the latches 96 against the lateral lugs 75 of the automatic tuning keys 15, which are differentiated in Fig. 15 by the suffix letters a-e. Therefore, as long as the time-controlled mechanism is in operation, 65 it is impossible to push down the keys 14 and 15.

The circuits of the electric motors 35 and 172 and the solenoid 218e remain closed until the contact piece 204 on the rotating disk 201e bridges the switch arms 210e. When that occurs 70 the circuit of solenoid 153 is closed as follows: From circuit lead 234 to point 247, wire 246, through solenoid 153, wires 245 and 243, across the connected switch arms 210e to return lead 235. When the solenoid 153 is ener- 75

gized, it rocks the arm 143 and opens the two switch contacts 145—150. This breaks the motor and clutch circuits, so that the radio shaft 158 is automatically stopped in correct tuning position. The circuit through solenoid 218e is opened when the clock-driven switch arm 133 moves out of contact with the radial strip 129. When the energized solenoid 153 rocks the arm 143 to open the various circuits mentioned, it closes the switch contacts 144 and 148 to energize the solenoids 116, which operate the restoring rod 107. Since, however, no tuning key 15 was actuated, this movement of rod 107 is an idle one.

The circuit connections that have been described for plug 22e are the same for the other four plugs 22a—22d, except that each particular plug closes the circuit through a corresponding solenoid 218a—218d. For instance, at eight o'clock the rotary switch arm 133 cooperates with plug 22c to close the circuit through solenoid 218c, whereupon the contact arms 219c are thrown against the associated tuning disk 231c and the switch 223c is closed to complete the motor and clutch circuits in the manner already described. It will not be necessary to repeat in detail the circuit connections for solenoid 218c, because they are evident from Fig. 15. At nine o'clock, the inserted plug 22b energizes solenoid 218b; at ten o'clock, the solenoid 218d is energized; and at eleven o'clock, the circuit is closed through solenoid 218a. Since the contact piece 204 in each tuning disk 201 is inserted in tuning position for a particular station, the radio shaft automatically stops in tuning position when a pair of actuated switch arms 213a—213e is bridged by the contact piece 204 of the associated disk. I might explain here that in Fig. 15 I have purposely shown the contact pieces 204 as mere inserts in the periphery of the disks, it being understood that these contact pieces may be circumferentially adjustable, as previously explained in detail.

It is clear from the preceding description that a person can provide himself with an entire evening's (or a whole day's) program of selected radio reception by the simple expedient of inserting the plugs 22 in the appropriate jacks. This operation is so simple that a child can do it. Since city newspapers publish daily complete radio programs, a person can make his selections every morning, afternoon or evening to bring in automatically the desired stations in predetermined sequence. If one station is to be repeated at a later interval, it is only necessary to insert a second plug in the same circle of jacks. The front panel 10 of the control cabinet C should be appropriately marked to indicate the stations represented by the circles of jacks, as for example, as shown on Fig. 1, the station call-letters WEAF, WJZ, etc., have been applied to the respective circles of jacks. Call letters of other stations that may be more desirable to the listener may be inscribed in place of those shown, or else station wave lengths may be employed. The control cabinet can be made as ornamental as desired, and it may be put in any convenient place, as on a mantel, shelf, table, desk, chair, or where not. Incidentally, the cabinet performs the additional function of a clock.

When the time-controlled mechanism is not wanted, the toggle lever 23 is thrown into "off" position, as shown in Fig. 1, whereby the keys 14 and 15 are released for operation because the

solenoids 62 and 92a—92e are de-energized by the opening of switch 230. The key 14 is held down until the desired station is tuned in. When this key is operated, the motor and clutch circuits are closed as follows: From the main lead 234, wire 239, through closed switch contacts 69 and 68, wire 238, through the windings of electric motors 35 and 172 in parallel, and from there through wires 236 and 237 to the return lead 235. At the same time the circuit of clutch 180 is closed through wires 238, 241 and 240, as previously described. As soon as the desired station is tuned in, the key 14 is released, whereupon the switch contacts 68—69 are instantly opened to break the motor circuit and stop the radio shaft in tuning position. In receivers of the present day, it is not necessary to adjust the tuning shaft with microscopic accuracy, because a certain amount of broad tuning is not only permissible but actually desirable for better reproduction. Therefore, when a person holding down key 14 hears the broadcast reception that he wants, he simply releases the key.

The automatic tuning keys 15 in this instance represent the same five stations as the five circles of jacks 21 of the time-controlled mechanism, but it is evident that they may represent five other stations. In that case, however, it will be necessary to have five additional tuning disks 201 for those other stations. The purpose of the tuning keys 15 is to enable a person to bring in a desired station without regard to time. Referring to Fig. 15, let us say that the key 15a is actuated to bring in the station represented by that key. When the switch contacts 86a are closed by key 15a, the circuit of solenoid 218a is closed as follows: From main lead 234 to point 269, wire 268, solenoid 218a, wire 270, through closed switch contacts 86a, and from there through wire 254 to the return lead 235. When solenoid 218a is energized, it operates in the manner previously described to move the switch arms 210a against the tuning disk 201a and at the same time close the switch contacts 223a. The closing of switch contacts 223a cuts the electric motors 35 and 172 into circuit, while at the same time closing the circuit of clutch 180. The motor and clutch circuits are interrupted when the contact piece 204 of disk 201a spans the switch arms 210a, as above described in connection with the clock-controlled mechanism. When any one of the other keys 15b—15e is actuated, the circuit is closed through the corresponding solenoid 218b—218e. These circuit connections need not be described, because they are easily traced in Fig. 15. It is therefore clear that the tuning connections associated with the radio shaft 158 are independently controlled by the clock mechanism through plugs 22 and by the selective keys 15.

When a tuning key 15 is actuated, the associated latch 101 snaps into locking engagement with the rear end of the key and holds it down even when the key is released. When the solenoid 153 is energized on the opening of the motor and clutch circuits, as previously explained, the normally open switch contacts 144 and 148 are closed to energize the solenoids 116, whereupon the shaft 107 is rocked rearward to throw the actuated latch 101 back to normal releasing position. The previously depressed key 15 is therefore automatically restored to normal position after the desired station has been tuned in. Before leaving Fig. 15, I might explain that the dotted line D indicates diagrammatically the separation of the control cabinet from the receiver—

that is, what is above the line D is in the receiver cabinet, and what is below the line is in the remote control cabinet. The wires crossing line D are supposed to be an electric cable connecting 5 the two cabinets. Of course, the control cabinet could be mounted on the radio cabinet, or even made a part thereof, but I prefer to have the control cabinet separate, so it can be moved about to any convenient place.

10 Although I have shown and described certain specific mechanisms, I want it understood that my invention is not limited to the details set forth. I realize that the basic features of my automatic tuning apparatus may be mechanically embodied in various forms without departing 15 from the scope of the invention as defined in the appended claims. Furthermore, it is evident that some features of this invention may be used without others.

20 I claim as my invention:

1. The combination of a radio tuning shaft, mechanism for actuating said shaft to a plurality of different positions to tune in certain stations, clock-controlled connections for energizing said 25 actuating mechanism at predetermined intervals, key-controlled connections for energizing said actuating mechanism independently of said clock-controlled connections, and means for preventing operation of said key-controlled connections 30 when the clock-controlled connections are in operative condition.

2. A tuning unit operable at a distance from a radio receiver and adapted to be electrically connected therewith, said unit comprising a set of 35 clock-controlled switches for causing operation of the tuning shaft at predetermined intervals to tune in one or more selected stations, a separate set of manually operated switches in said unit each for tuning in a desired station independently 40 of said clock-controlled switches, and means for preventing operation of either one of said sets of switches when the other set is used.

3. The combination of a radio tuning shaft, an electric motor for operating the same, a series of 45 contacts mounted on said shaft in predetermined angular relation, a pair of spaced members constituting a normally open switch associated with each contact, said switches being mounted to have independent movement and normally held out of the path of said contacts, an electromagnetic device for controlling the position of each switch, electrical connections for closing the motor circuit to 50 actuate said shaft, selectively controlled mechanism for energizing any one of said devices to move the associated switch into the path of the adjacent contact, and means whereby the motor circuit is automatically broken when the spaced members of the actuated switch are bridged by the associated contact.

60 4. The combination of a radio tuning shaft, an electric motor for operating said shaft, a series of contacts mounted on said shaft in predetermined angular relation, a pair of spaced members constituting a normally open switch associated with 65 each contact, said switches being mounted to have independent movement and normally held out of the path of said contacts, an electromagnetic device for controlling each switch, electrical connections for closing the motor circuit to actuate said shaft, time-controlled mechanism for actuating a plurality of said devices at different intervals to move the associated switches into the path of their respective contacts, means whereby the motor circuit is automatically broken when 70 the spaced members of an actuated switch are

bridged by the associated contact, and manually operable connections associated with said mechanism for predetermining the time and sequence of operation of said switches, so that a plurality of selected stations are automatically tuned in at 5 the desired intervals.

5. The combination of a radio tuning shaft, means associated with said shaft for stopping the same in any one of a plurality of predetermined tuning positions, time-controlled mechanism for operating said means at predetermined moments, key-controlled connections for operating said means independently of said time-controlled mechanism, and means for preventing actuation of the key-controlled connections while 10 the time-controlled mechanism is in operation.

6. The combination of a radio tuning device, means associated with said tuning device for adjusting the same to any one of a plurality of predetermined tuning positions, time-controlled 20 mechanism for operating said means at predetermined moments, key-controlled mechanism and connections therefor for operating said means independently of said time-controlled mechanism, means for preventing actuation of 25 the key-controlled mechanism while the time-controlled mechanism is in operation, and switch means operative at will which in one position renders effective only the time-controlled mechanism and in the other position renders effective 30 only the key-controlled mechanism.

7. In radio tuning apparatus, the combination of a plurality of devices representing certain stations, tuning mechanism controlled by said devices, time-controlled means for energizing one 35 or more of said devices at predetermined intervals, manually operable means for selecting the devices to be energized, manually controlled switches for selectively energizing said devices independently of said time-controlled means, 40 and means for preventing operation of said switches when said devices are under the control of said time-controlled means.

8. In a radio receiver, a tuning shaft carrying an insulating disk, a contact member supported 45 on said disk for movement therewith and circumferentially adjustable thereon, said member having a resilient portion, means on said disk arranged to be engaged by said resilient portion which presses against said means for frictionally holding the contact member in adjusted position to represent a selected station, a normally open switch adapted to be closed by said member, and means controlled by said switch for automatically stopping said shaft in tuning position for the 50 station represented by said member.

9. The combination of a radio receiver having a tuning shaft rotatable in opposite directions through a predetermined arc, an electric motor for operating said shaft, means for automatically 60 reversing the rotation of said shaft at each end of its arc of travel, a box located at a distance from said receiver and operatively connected thereto by electric conductors, a set of keys carried by said box and representing each a certain station, 65 switch means controlled by each key for closing a circuit to energize said motor and operate said shaft, electromagnetic means controlled by an actuated key to automatically stop said shaft in tuning position for the station represented by 70 said key, a separate key on said box, a circuit different from the first mentioned motor circuit directly connected to the motor, and switch means controlled by said separate key for continuously energizing said last mentioned motor 75

circuit whereby the tuning shaft will be actuated without interruption in either direction so long as said separate key is maintained in operative position.

- 5 10. In radio tuning apparatus, the combination of a rotary tuning shaft, an electric motor for operating said shaft, a plurality of contacts, insulated from each other and from the shaft, rotatable with said shaft and so positioned as to 10 represent certain stations, a normally open switch device associated with each contact and adjustably mounted to move into and out of the path of said contact, means for normally holding each switch device out of the path of the associated 15 contact, selectively operable means for moving any switch device into the path of the associated contact, and circuit connections for stopping said motor when one of said contacts engages the associated switch device.
- 20 11. In radio tuning apparatus, the combination of a rotary tuning shaft carrying a plurality of insulating disks, means for operating said shaft, a contact carried by each disk in predetermined position to represent a selected station, 25 a pair of insulated switch members associated with each disk and adjustably mounted to move into and out of engagement with said disk, means for normally holding each pair of switch members away from the associated disk, selectively 30 operable means for moving any pair of switch members to engage the associated disk and the contact carried thereby, and connections whereby said shaft automatically stops in selected tuning position when a pair of said switch members engage the associated contact.
- 35 12. As a new article of manufacture, a remote control box having means for electrically connecting it with a radio receiver and containing a clock, a plurality of switches selectively controlled by said clock for causing one or more stations to be automatically tuned in at predetermined intervals, a plurality of station-selecting keys carried by said box and manually operable independently of the clock to bring in a desired 40 station at any time, and means for preventing operation of said station-selecting keys when the switches are under the control of the clock.
- 45 13. As a new article of manufacture, a remote tuning device for radio receivers comprising a cabinet, a clock in said cabinet, the clock dial being surrounded by a plurality of holes arranged in concentric circles, each hole having associated with it a normally open switch, a plurality of similarly constructed pegs movably 50 mounted in said holes to close the switches for preselecting certain stations to be tuned in at certain intervals, and a set of keys projecting from said cabinet and manually operable to tune in a desired station independently of the clock, 55 and means for preventing operation of said manually operable keys so long as the normally open

switches and the pegs are under the control of the clock.

14. In combination with a radio receiver set having a tuning element, an electric driving motor having a plurality of selectively operable control circuits with controls located at a point remote from said receiver, means controlled over each circuit and acting upon operation of the control point to energize said motor to move it a predetermined distance, means rendered effective by 10 said motor upon movement of said predetermined distance for de-energizing the operating circuit of said motor, means for predetermining said distance and for making it different for each of said control circuits, a mechanical connection 15 between said motor and said tuning element, and additional means rendered effective by the de-energization of the operating circuit of said motor for causing the disengagement of the connection between said motor and said tuning element 20 whereby tuning of the radio receiver set may be effected.

15. In combination with a radio receiver set having a tuning element mounted on a rotatable shaft, an electric driving motor having a plurality of selectively operable control circuits with controls therefor located at a point remote from said receiver, means controlled over each circuit and acting upon operation of said control points through suitable relays located in the circuit to 25 energize said motor and move it a predetermined distance, means rendered effective by said motor upon movement of said predetermined distance for de-energizing the operating circuit of said motor, means for predetermining said distance 30 and for making it different for each of said control circuits, a mechanical connection between said motor and said tuning element, and additional means rendered effective by the de-energization of the operating circuit of said motor for 35 causing the connection between said motor and said tuning element to be disengaged whereby tuning at the radio receiver set may be effected.

16. In radio tuning apparatus, the combination of a rotary tuning shaft, an electric motor for 45 selectively operating said shaft through predetermined fractions of a revolution, a plurality of disk members carried by and rotatable with said shaft, an insulated contact adjustably mounted on the periphery of each disk member, the several 50 contacts being arranged in predetermined angular relation, manually operable means at a remote point and means under the control of said last means for closing a circuit to energize the motor, and adjustable means in cooperative relation with each disk member for causing the 55 motor circuit to be selectively de-energized upon rotation of said disk members to predetermined positions at which their contacts and the adjustable means are in contacting relation.

60 ADOLPH A. THOMAS.
